Application May 4, 1943, Serial No. 110,112

(Cl. D3—13)

To all whom it may concern:

Be it known that we, Paul M. Maxwell and Wilhelmina J. Russy, each a citizen of the United States, residing, respectively, at Manhasset, county of Nassau, and State of New York, and at Jersey City, county of Hudson, and State of New Jersey, have invented a new, original and ornamental Design for a Hat, of which the following is a specification, reference being had to the accompanying drawing, forming part thereof.

Figure 1 is a top view of a hat showing our new design.

Fig. 2 is a front view thereof, and

Fig. 3 is a side view of the hat shown in Fig. 1, on a smaller scale.

Our design comprises a soft hat of the type disclosed with an ovular, segmented crown having buttons centered at the base of each triangular segment so that they extend in a uniformly spaced row around the crown below the upturned, stitched brim, said brim being of greater width in front and extends in a continuous curve upwardly and outwardly from the crown, the front being higher than the sides or back, all as shown.

We claim:

The ornamental design for a hat, as shown and described.

PAUL M. MAXWELL,
WILHELMINA J. RUSSY.
